(57) **CLAIM**

The ornamental design for a unitary foam bed resiliency element, as shown and described.

DESCRIPTION

FIG. 1 is a top, front, left side perspective view of a unitary foam bed resiliency element of our new design.

FIG. 2 is a bottom, right, back side perspective view thereof.

FIG. 3 is a top plan view thereof.

FIG. 4 is a bottom plan view thereof; and,

FIG. 5 is a front side elevational view thereof, the back, right, and left side being an identical image thereof.

The broken lines are for environmental purposes only and form no part of the claimed design.
